GROOVED TACK

Geoffrey Coleman, Leicester, England, assignor to United Shoe Machinery Corporation, Flemington, N. J., a corporation of New Jersey

Application September 13, 1955, Serial No. 37,899

Term of patent 14 years

Claims priority, application Great Britain March 30, 1955

(Cl. D54—9)

Fig. 1

Fig. 2

Fig. 3

Fig. 4

Fig. 5

Fig. 1 is a front elevational view of a grooved tack showing my new design;

Fig. 2 is a side elevational view thereof;

Fig. 3 is a plan view of the tack;

Fig. 4 is a bottom plan view, and

Fig. 5 is a perspective view partly broken away to show the cross-sectional configuration.

The tack is of arbitrary over-all length.

I claim:

The ornamental design for a grooved tack, substantially as shown and described.
